CAN STACKING MACHINE

John E. Socke, Pelham Manor, N. Y., assignor to
 American Can Company, New York, N. Y., a
 corporation of New Jersey

Application March 30, 1945, Serial No. 585,665

11 Claims. (Cl. 226—14)

1
 The present invention relates to a machine for stacking containers or cans and has particular reference to mechanism for positioning the cans in a predetermined arrangement for packing into paper bags prior to shipment or storage.

Empty cans are usually shipped and stored in sealed paper bags for convenience in handling and to keep the cans clean during transportation. For best results in making a firm and compact package, the cans are arranged in the bag in an orderly manner, the cans being stacked in a plurality of layers. The arrangement and number of cans in each layer depends entirely upon the size of the cans being packed. Such an arrangement in each layer may be a plurality of rows of an equal number of cans in each row in a staggered or straight layout or may be rows of an unequal and an equal number of cans in each alternate row and in a staggered layout.

The instant invention contemplates a mechanism for arranging the cans in a staggered layout of a plurality of rows having an unequal and an equal number of cans in alternate rows.

An object of the invention is the provision of a mechanism for placing cans in a predetermined arrangement for packing into paper bags for shipment and storage wherein the cans are received in a moving procession and are segregated into rows having an unequal and an equal number of cans in each alternate row and the rows formed into a staggered layout or arrangement, best fitted as to economy of space and compactness, to be transferred as a unit layer into the bag.

Another object is the provision of such a mechanism wherein rows of equal and unequal numbers of cans may be alternately segregated so that a desired pattern of can arrangement may be obtained to form a staggered layout.

Another object is the provision of a mechanism of this character wherein the rows of cans alternating in equal and unequal numbers are arranged in a staggered layout in proper sequence and in timed order so that the desired can pattern will result.

Numerous other objects, and advantages of the invention will be apparent as it is better understood from the following description, which, taken in connection with the accompanying drawings, discloses a preferred embodiment thereof.

Referring to the drawings:

Figure 1 is a top plan view of a machine embodying the instant invention, with parts shown in section and with parts broken away, the view including a wiring diagram of the electric apparatus used in the machine;

2
 Fig. 2 is a sectional view taken substantially along the line 2—2 in Fig. 1; and

Figs. 3 and 4 are views similar to Fig. 1, with certain of the movable parts in different positions.

As a preferred embodiment of the instant invention the drawings illustrate a machine in which cylindrical cans A are stacked into a loading tray B in a staggered layout as shown in dotted lines in Fig. 1 so that they may be transferred in any suitable manner, as a unit layer into a paper bag for shipment or storage.

The cans to be stacked are received in procession order moving in a straight line along a runway which includes a pair of spaced and parallel guide rails 11 (Fig. 1). The cans are in an upright position and are supported on a continuously moving belt conveyor 12 which is disposed between the guide rails. The belt carries the cans into the machine along a straight line 15 path of travel extending between the loading tray B and a pusher or segregating member 13 which is located in front of the tray. A stop element 14 disposed adjacent a side of the tray (at the right as viewed in Fig. 1) stops the line of cans entering 20 the machine in a predetermined position relative to the tray in readiness to be pushed into the tray by the pusher 13.

The loading tray B is rectangular in shape and is of sufficient dimensions to hold a full unit 30 layer of cans A. In the instant case, by way of example, the tray is designed to hold six rows of cans in staggered arrangement, the first row containing six cans, the second row five cans and thus alternating for the full six rows.

The front of the tray B is open, while its other three sides are formed with upright retaining walls 17, 18, 19. The bottom of the tray is supported on a machine frame 21 and is formed with a pair of spaced and parallel depending slide 40 rails 22 which operate in longitudinal slide ways 23 formed in the top of the machine frame.

To receive alternate rows of cans of equal and unequal numbers in staggered or nesting relation, the loading tray B is shifted sidewise, longitudinally of the machine for each row of cans to be received and in time with the reception of the cans. For this purpose the machine is equipped with a pair of air operated or pneumatic tray cylinders 26, 27. These cylinders are secured to the top of the frame 21, adjacent the respective retaining walls 17, 19 of the tray.

The tray cylinder 26 constitutes a pneumatic cushioning device and is provided with a piston 31 having a rod 32 which is secured to the retaining wall 17 of the tray. The outer end of the

cylinder is connected to a pipe 33 which constitutes an air line and which leads from any suitable source of compressed air. The air continuously exerts its pressure against the piston 31 and thus tends to force the tray toward the right as shown in Fig. 1 and to maintain it in this position against a stop pin 35 secured in the top of the frame 21. This is the position of the tray when it receives a row of six cans.

The tray cylinder 27, disposed adjacent the opposite side of the tray B, is of considerably larger diameter than the cylinder 26 and constitutes a pneumatic ram. The cylinder 27 is provided with a corresponding larger diameter piston 37 having a rod 38 which is secured to the retaining wall 19 of the tray. The outer end of this cylinder is connected by an air pipe 39 to a valve housing 41. The housing is formed with an air channel 42 which at one end communicates with the air pipe 39 and which at the opposite end communicates with a pipe 43. One end of the pipe 43 is secured in the housing while its opposite end connects with and receives air from the main air line pipe 33.

The valve housing 41 encloses a slide valve 44 which extends across the air channel 42 and which normally closes off the channel so that the air from the line 33 is prevented from entering the cylinder 27 when the tray is in the position shown in Fig. 1. The valve is formed with an actuating stem 46 which is connected to the movable core of a normally deenergized electric solenoid 47 indicated in the wiring diagram. A compression spring 48 in the solenoid presses against its core and normally keeps the air valve closed.

The valve stem 46 is also connected to a lever 49 which is pivoted on a lug 51 formed on the valve housing 41. The opposite end of the lever carries a vent cap 52 which is adjacent a vent port 53 formed in the housing. This vent port communicates with the air channel 42.

When the tray solenoid 47 is energized, by electric circuits hereinafter explained, it shifts the valve 44 to open position and closes the vent port 53 in the valve housing 41 and thus permits compressed air from the main air line 33 to flow into the tray cylinder 27. This air exerts itself against the piston 37. Since this piston is larger in area than the piston 31 in the small tray cylinder 26, the air forces the tray toward the left as shown in Fig. 4, against the resistance of the air acting against the smaller piston 31 until the tray comes against a stop pin 55. This is the position of the tray when it is receiving a short row of five cans. The tray remains in this position as long as the valve 44 stays in open position.

After the tray has received a short row of cans, the solenoid 47 is deenergized and the spring 48 thereupon pushes the valve 44 into closed position. This cuts off the supply of air to the large tray cylinder 27. This same movement of the valve opens the vent port 53 and thus releases the air in the large cylinder. With the large cylinder thus opened to the atmosphere, the compressed air acting against the piston in the small cylinder immediately returns the tray to its original position, as shown in Fig. 1, in readiness to receive another long row of six cans. In this manner the tray is shifted laterally through successive alternating strokes into a position to receive a long row of cans and then into a position to receive a short row until the tray is completely filled. The entire unit layer of cans is then re-

5 moved in their staggered relation in one batch, in any suitable manner.

The stop element 14 which stops the line of cans entering the machine in the proper location relative to the tray for deposit thereinto, moves with the tray in order to effect this operation, although it should be understood that the stop element could be actuated equally well by any other means as long as it shifts in time with the tray. The stop element 14 is disposed in longitudinal alignment with the path of travel of the cans A entering the machine and is formed on the inner end of a rod 61 (Fig. 1), loosely carried in a slide bar 62 which rests on and slides along a slide plate 64 bolted to the top of the main frame 21.

10 A compression spring 66 surrounding the stop rod and interposed between the stop element and the slide bar forms a yieldable connection between these two parts. The travel of the rod within the slide bar is limited by a collar 67 which is carried on the outer end of the rod. The outer end of the rod also carries a movable switch element 68 of a normally open actuating electric switch 69 having contacts 71, 72. This switch is mounted on a pad 73 formed on the slide bar 62 and thus moves with the bar.

15 The slide bar 62 is connected to the inner ends of a pair of spaced and parallel actuating arms 75, 76 which constitute a parallelogram mounting disposed adjacent the retaining wall 19 of the loading tray B. The outer ends of the arms are mounted on pivot studs 77 threaded secured in the top of the main frame 21. The arm 76 intermediate its length is connected by a link 78 to the retaining side wall 19 of the tray.

20 Hence as the tray B shifts from side to side to receive long and short rows of cans, the arms 75, 76 rock on their pivot studs 77 and thus shift the slide bar 62 and its stop element 14 in time with the tray and in the same direction. The stop element 14 is normally located so that when the tray is in position to receive a long row of cans (which just fills the width of the tray) its can engaging face is substantially flush with the inside surface of the retaining wall 19 of the tray (Fig. 1).

25 When the tray B shifts toward the left a distance equal to substantially one-half the diameter of a can (as viewed in Fig. 1) into a position to receive a short row of cans which will be in nested or staggered relation to the long row, the stop element 14, through its connection with the tray, moves inwardly or to the left a distance 30 equal to the full diameter of a can to be stacked (Fig. 4). With the stop element in this position the line of incoming cans is stopped a half a can diameter short of the inner surface of the retaining wall 19 of the tray and hence these cans 35 will be in a staggered relation to the long row which is already in the tray, also as best seen in Fig. 4. In this manner a different number of cans are in alternate rows and this is effected merely by the shifting of the stop element with the tray.

40 The spring 66 against which the stop element 14 operates is made strong enough to hold back a line of incoming cans which is in excess of those required to make up a full row of cans to be deposited in the tray. This insures that there will 45 always be a full row of cans inserted in the tray and that the cans are in touching engagement. Hence if there is a break in the line of incoming cans, this break must be filled by the cans coming 50 to rest against the stop element and stacking up

one behind the other until a line of sufficient length to overcome the resistance of the spring 66 is assembled. When such a line is created the pressure of the cans against the stop element 14 will shift the stop element sufficiently to close the electric switch 69 and this establishes certain electric circuits, shown in the wiring diagram, to set the pusher member 13 in operation to insert the cans into the tray.

The pusher member 13 extends for nearly the full width of the loading tray B and is disposed in an elevated position so that it can move across the can belt conveyor 12 and clear the conveyor and the stop element 14 when positioned for a short row of cans, without interference. The pusher is mounted on the inner ends of a pair of spaced and parallel support bars 82, 83 (Fig. 1) which slide in bearing blocks 84 formed on a frame extension 85 (Fig. 2) of the main frame 21. The pusher is shifted through an inner or can pushing stroke and thence through an outer or return stroke by a pusher air cylinder 86 which is mounted on the top of the frame extension 85.

The pusher cylinder 86 is equipped with a piston 87 which is formed on a piston rod 88 which extends beyond the inner end of the cylinder. This end of the rod is secured to a cross plate 89 which is connected by a pair of spaced, long shoulder bolts 91 to the pusher member 13.

The piston 87 is reciprocated within the cylinder by compressed air acting against one or both faces of the piston. For this purpose air is continuously introduced into the inner end of the cylinder by a pipe 92 which connects with the main air line 33 and receives compressed air from this line. Compressed air under the same pressure is also introduced, periodically, into the outer end of the cylinder by way of a short pipe 93 which is connected into a valve housing 94. The valve housing is also connected by way of a pipe 95 to the pipe 92.

The valve housing 94 is similar to the valve housing 41 and is formed with an air channel 96 which communicates with the housing ends of the pipes 93, 95. The channel also communicates with an atmosphere vent port 97 formed in the housing. The channel is normally closed off by a slide valve 98 which extends across the channel. This valve is formed on a rod 99 which is connected to a movable core of a normally de-energized electric solenoid 101 which is included in the circuits shown in the wiring diagram in Fig. 1.

A compression spring 102 housed within the solenoid 101 presses against its core and thus keeps the valve in closed position when the solenoid is deenergized. The valve rod 99 is also connected to a lever 104 which is pivotally mounted on the valve housing and which carries on its opposite end a vent cap 105 for closing the vent port 97 when the valve is open.

Hence compressed air continuously admitted into the inner end of the cylinder 86 acts against the inner face of the piston 87 to keep the pusher in its normally retracted position. When a row of cans is to be segregated from the line of incoming cans and is to be inserted into the tray B, the pusher solenoid 101 is energized and this moves the slide valve 98 to open position in the housing channel 96 and thus permits air from the pipe 95 to flow through the valve housing 94 and pipe 93 into the outer end of the cylinder.

This air acts against the outer face of the piston and the area of the outer face is greater than that of its inner face by the amount taken up

by the cross sectional area of the piston rod. Therefore the force against the outer face is greater than that against the inner face and thus the piston is moved inwardly in the cylinder. This movement of the piston forces the pusher 13 against the cans on the conveyor belt 12 and thus shifts them from the belt into the loading tray B and leaves them just inside the edge of the front of the tray.

The pusher member 13 only pushes into the tray those cans which are disposed in front of the pusher end which are in line with the tray. During this inserting operation a stop projection 106 formed on the left side of the pusher (as viewed in Fig. 1) moves in front of the cans remaining on the conveyor and holds them back until the pusher is withdrawn for the next inserting stroke. It should be noticed that the outer edge of this stop projection is disposed in a line extending just inside the inner surface of the retaining wall 17 of the tray. This is so that the pusher will engage all the cans when a long row is to be pushed into place and will cut off the last can in the line when the tray B and the stop element 14 are shifted a half can diameter and a full can diameter respectively, for a short row of cans.

When the row of cans inserted into the tray B is fully in place, the pusher solenoid 101 is de-energized and its spring 102 shifts the valve into closed position and thus cuts off the flow of air into the outer end of the cylinder. This action also opens the vent port 97 and thus releases the air in this end of the cylinder to the atmosphere. Hence the air in the inner end of the cylinder returns the piston 87 and the pusher member 13 to their original retracted position. This removes the stop projection 106 on the pusher from the path of travel of the cans and thus permits the incoming cans to again move into place in front of the pusher and to engage against the movable stop element 14. On subsequent inserting strokes of the pusher 13 the cans being inserted into the tray engage against those previously positioned in the tray and thus push the positioned cans toward the rear of the tray until the entire tray is filled.

A movable or depressible guide rail 111 is disposed in front of the pusher member 13 and forms a continuation of one of the conveyor guide rails 11 to keep the incoming cans in a straight line as they enter into the space between the tray and the pusher. This guide rail is disposed in a slot 112 formed in the top of the main frame 21 and is carried on a vertical support rod 113 (Fig. 2) which slides in a bearing 114 formed on the frame. The lower end of the rod is connected to a movable core 115 of a normally deenergized electric solenoid 116 secured to the frame. A compression spring housed within the solenoid and acting against the lower end of the core keeps the guide rail 111 in a normally raised position to guide the incoming cans.

Just prior to a can pushing stroke of the pusher member 13, the guide rail solenoid 116 is energized and this draws the guide rail 111 downwardly in its slot 112 so that the cans being inserted into the tray will clear the rail without interference. When the pusher member returns to its normal retracted position the guide rail solenoid is deenergized and its spring returns the rail to guiding position for the incoming cans.

Reference should now be had to the wiring diagram in Fig. 1. The cycle of operation of the machine is started by the closing of the stop ele-

ment switch 69 which is effected by the line of cans entering the machine, as hereinbefore explained. The loading tray B is in the position shown in Fig. 1 and the pusher member 13 is in its normal retracted position. The stop switch 69 forms a part of a relay circuit D which includes a pair of double pole electric switches 121, 122 having movable elements 123, 124 respectively which are actuated by the loading tray B. When the tray is in the position shown in Fig. 1 the movable element 123 closes against a pair of contacts 125, 126 and the movable element 124 closes against a pair of contacts 127, 128. When the tray shifts toward the left into the position shown in Fig. 4 the movable element 123 closes against a pair of contacts 131, 132 and the movable element 124 closes against a pair of contacts 133, 134.

The relay circuit D further includes a triple pole cam operated switch 136 and a relay 137. The triple pole switch is equipped with two movable elements 138, 139. This circuit as well as all the other circuits to be hereinafter described receive electric energy from a generator circuit which includes a generator 141 connecting with a main lead wire 142 and a return lead wire 143.

When the stop switch 69 closes, through the pressure of the cans A on the belt conveyor 12 pressing against the stop element 14 and connected parts, electric energy from the main lead wire 142 flows through the relay circuit D along a wire 145 connecting the lead wire 142 with the contact 125 of the tray switch 121. This energy passes along the switch element 123, contact 126, connecting wires 146, 147 to contact 127, switch element 124 and contact 128 of the tray switch 122, a wire 148 and contact 134 also of switch 122, a connecting wire 149 to contact 71 of the stop switch 69, through the switch element 68, contact 72, a connecting wire 151 to the relay 137 and thence by way of a wire 152 to the main return lead wire 143.

Electric energy passing along this relay circuit D energizes the relay 137 and this establishes three new circuits, a guide rail circuit E, a pusher actuating circuit F and a holding circuit G. For this purpose the relay is formed with three movable switch elements 155, 156, 157 which close against switch contacts to simultaneously establish these three circuits.

Switch element 155 of the energized relay 137 closes against a pair of contacts 158, 159 which establishes the guide rail circuit E. Electric energy then flows from the main lead wire 142 along a connecting wire 161, through a pair of contacts 162, 163 and movable element 138 of the cam operated switch 136, a connecting wire 164 to and through the guide rail solenoid 116, a connecting wire 165, through contacts 158, 159 and switch element 155 of the relay 137 and thence by a wire 166 to the return lead wire 143. Electric energy passing along this circuit energizes the guide rail solenoid 116 and thus pulls down the guide rail 111 clear of the cans on the belt conveyor 12, as hereinbefore explained.

In the pusher actuating circuit F, the movable element 156 of the energized relay 137 closes against a pair of contacts 171, 172 to establish this circuit. With this switch closed, electric energy from the main lead wire 142 passes along a connecting wire 173, contacts 171, 172 and element 156 of the relay 137, a connecting wire 174 to and through the pusher valve solenoid 101, and thence by a connecting wire 175 to the return

lead wire 143. Electric energy passing along this circuit energizes the valve solenoid 101 and thus shifts the valve 98 to open position and admits air into the pusher cylinder 86 to actuate the pusher 13 through an inward or can pushing stroke as hereinbefore explained.

The holding circuit G is established to hold the guide rail circuit E and the pusher actuating circuit F closed during the full inward movement 10 of the pusher member 13 since during this movement the cans are shifted out of engagement with the stop element 14 and this allows the stop switch 69 to open. Without the holding circuit G, the opening of the stop switch would immediately 15 deenergize the other circuits.

To establish the holding circuit G the movable element 157 of the relay 137 closes against a pair of contacts 177, 178. With this switch closed 20 electric energy from the main lead wire 142 passes along the connecting wire 161, through contacts 162, 163 and element 138 of the cam operated switch 136, a connecting wire 179, through contacts 177, 178 and element 157 of the relay 137, a connecting wire 180, through the relay 137 and 25 thence through the wire 152 to the return lead wire 143. Electric energy passing along this circuit keeps the relay 137 energized after the stop switch 69 opens as above mentioned.

When the pusher member 13 has reached the 30 end of its can pushing stroke, i. e., when the cans are in fully inserted position in the loading tray B, as best shown in Fig. 3, all three circuits E, F and G are broken simultaneously to return the pusher member 13 and the guide rail 111 to their original 35 positions in readiness for the assembling and transfer of another row of cans. This is brought about by cam action. For this purpose the pusher support rod 83 carries a tapered cam 182 (Fig. 1) which moves with the rod.

When the pusher 13 nears the end of its inward 40 stroke the cam 182 rides under a roller 183 carried by the movable elements of the switch 136 and forces the roller and its attached switch elements outwardly. This cam action moves the 45 switch element 138 of the switch 136 away from its contacts 162, 163 and thus breaks the holding circuit G. This deenergizes the relay 137 and thus opens all the relay switches 155, 156, 157. Hence all circuits are broken. The spring 102 50 in the pusher solenoid 101 returns the valve 98 to closed position and opens its vent port 97 to allow the pusher 13 to return to its retracted position and the spring in the guide rail solenoid 116 returns the guide rail 111 to can engaging and 55 guiding position, as explained above.

When the switch element 138 of the cam operated triple pole switch 136 moves away from the contacts 162, 163 it momentarily closes against a pair of contacts 185, 186 of the switch 136 which 60 establishes an auxiliary relay circuit H which includes a portion of the main relay circuit D. This auxiliary relay circuit includes an auxiliary relay 187 having two movable switch elements 188, 189.

65 While the switch element 138 of the switch 136 is closed against the contacts 185, 186, electric energy from the main lead wire 142 passes along the wire 145 of the main relay circuit D, contacts 125, 126 and switch element 123 of the tray switch, a connecting wire 191, through contacts 185, 186 and switch element 138 of the switch 136, a connecting wire 192, auxiliary relay 187, a connecting wire 193, and thence by wire 152 to the return lead wire 143. Electric energy flowing along this 70 circuit energizes the auxiliary relay 187.

Energization of the auxiliary relay 187 closes its movable element 188 against a pair of contacts 195, 196 of a normally open holding circuit K which cuts out the cam operated switch 136 and also the tray switch contacts 125, 126 and 127, 128. Thus electric energy from the main lead wire 142 passes along a connecting wire 197, normally closed contacts 198, 199 and a movable switch element 201 of a normally deenergized breaker relay 202, a wire 203 connecting contact 199 with contact 195, contacts 195, 196 and switch element 188 of the auxiliary relay 187, a wire 204, auxiliary relay 187, and wires 193, 152 returning to the return lead wire 143. Electric energy passing through this holding circuit K keeps the auxiliary relay 187 energized when the cam 182 on the pusher support rod 83 moves away from the switch roller 183 and thus shifts the switch element 138 of switch 136 away from the contacts 185, 186 and returns it to closing position against the contacts 162, 163.

The energization of the auxiliary relay 187 also closes its switch element 189 against a pair of contacts 211, 212 and this establishes a tray shifting circuit L which includes the tray air valve solenoid 47. Thus while the auxiliary relay 187 is energized electric energy passes from the main lead wire 142 along the wire 161, a connecting wire 213, contacts 211, 212 and switch element 189 of the auxiliary relay 187, a connecting wire 214, tray solenoid 47, and thence returning along a connecting wire 215 to the return lead wire 143.

Electric energy passing along this tray shifting circuit L energizes the tray solenoid 47 and this shifts the tray air valve 44 into open position and thus admits air into the cylinder 27 to shift the loading tray B and the stop element 14 into the position shown in Fig. 4 to locate and receive a short row of cans as hereinbefore explained. The tray solenoid 47 is maintained in this energized condition by the holding circuit K during the segregating and inserting of the short row of cans into the tray so that the tray will be held stationary against the cushion of air in the small cylinder 26 and this is the proper position to receive the short row of cans.

Locating and pushing the short row of cans into the loading tray B as shown in Fig. 4 is effected in the same manner as for the long row and is brought about by the same circuits E, F and G which are used for the long row of cans. It should be noted, however, that when the tray is in the short row position shown in Fig. 4, the tray switch element 123 (Fig. 1) is away from the contacts 125, 126 and is closed against the contacts 131, 132 of this switch. Also the tray switch element 124 on the opposite side of the tray is spaced from the contacts 127, 128 of this switch and is against the contacts 133, 134.

Hence the relay circuit D used for energizing the main relay 137, to draw down the guide rail 111 through its solenoid 116 and also to operate the air valve 98 on the pusher air cylinder through its solenoid 101, now includes the contacts 131, 132, and 133, 134 of the tray switches 121, 122 instead of the contacts 125, 126, and 127, 128 in those switches.

Electric energy for energizing the relay 137 now passes from the main lead wire 142 along wire 145 of the relay circuit D, a connecting wire 221, contacts 131, 132 and switch element 123 of the tray switch 121, connecting wires 222, 223, contacts 133, 134 and switch element 124 of the tray switch 122, wire 149, contacts 71, 72 and switch element 68 of the stop switch 69, wire 151, relay

137, and wire 152 to the return lead wire 143 as in the original relay circuit D.

Energization of the main relay 137 through this new relay circuit D establishes the guide rail circuit E, the pusher actuating circuit F, and the holding circuit G in the same manner and for the same purpose also explained above. The only difference is that now a short row of cans is pushed into the tray instead of a long row.

When the short row of cans is fully positioned within the tray as when the pusher reaches the innermost extent of its inward travel, the cam 182 again engages the switch roller 183 and opens the switch 136, moving its switch element 138 away from the contacts 162, 163 to break the relay circuit D. This deenergizes the guide rail solenoid 116 and the pusher air valve solenoid 101 and thus returns the guide rail and the pusher to their original positions as hereinbefore explained.

There is one difference, however, that should be noted at this point in the operation of the electric apparatus and that is when the switch element 138 moves away from its contacts 162, 163 and closes against the contacts 185, 186, as hereinbefore explained, the auxiliary relay circuit H is not effected because the tray switches 121, 122 are not now closed against the contacts 125, 126 and 127, 128. These contacts are open and hence no circuit is completed. It will be remembered that the auxiliary relay 187 is already energized and is being maintained in that condition by the holding circuit K which keeps the tray in position to receive the short row of cans.

The loading tray B has now received its short row of cans and is therefore ready to be shifted back into its original position as shown in Fig. 1 to receive another long row of cans. This is brought about by the switch element 139 on the switch 136. This switch element closes against a pair of contacts 225, 226 in a breaker circuit M at the same time the switch element 138 closes against the contacts 185, 186. This is only of momentary duration and is brought about by the cam 182. During the time the contacts 225, 226 are closed, electric energy from the main lead wire 142 passes along wire 145 of the relay circuit D, wire 221, contacts 131, 132 and switch element 123 of the tray switch 121, wire 222, a connecting wire 228, breaker relay 202, contacts 225, 226 and switch element 139 of switch 136, returning along a connecting wire 229 to the return lead wire 143.

Electric energy passing along this circuit energizes the breaker relay 202 and moves its switch element 201 away from its contacts 198, 199. This opening of the breaker switch breaks the holding circuit K for the auxiliary relay 187 and thus deenergizes this relay and opens the switch element 189.

The tray shifting circuit L is thus broken and the tray solenoid 47 is thus deenergized. This permits the solenoid spring 48 to close the air valve 44 and open the vent 53 in the valve housing. The supply of air to the large tray cylinder 27 is thus cut off and the cylinder opened to atmosphere so that the air in the small cylinder 26 operates to shift the loading tray B back into the original position of Fig. 1.

The closing of the switch element 139 against the contacts 225, 226 takes place every time the switch 136 is opened by the cam 182 on the pusher support bar 83. However, the closing of these contacts only operates to form the breaker cir-

cuit M on every alternate stroke of the cam as when a short row of cans is to be inserted into the tray. This is when the tray switches 121, 122 are closed across the contacts 131, 132 and 133, 134. On other strokes of the cam, as when long rows of cans are being inserted into the tray, the tray switches 121, 122 are closed across the contacts 125, 126, and 127, 128 and thus no circuit can be established which includes the breaker relay 202.

This completes the cycle of operation of the machine for inserting two rows of cans into the loading tray B, a long row of six cans and a short row of five cans nesting in staggered relation thereto. The above explained operations are repeated for each set of two rows until the entire tray is filled with cans. The load of cans is then ready to be removed as a unit layer from the tray and placed in a paper bag for shipment or storage, but this forms no part of the present invention.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A machine for stacking cans in staggered rows, which comprises in combination, conveyor means for propelling cans to be stacked along a straight line path of travel, a tray having means for movably mounting the same adjacent one side of said path of travel for receiving said cans, a reciprocable pusher member disposed adjacent the opposite side of said path of travel for pushing a row of said cans transversely of said path of travel and into said tray, and means for shifting said tray in opposite directions relative to and longitudinally of said path of travel in time with the reception of each row of cans, the tray thereby receiving adjacent rows of cans in staggered relation.

2. A machine for stacking cans in staggered rows, which comprises in combination, conveyor means for propelling cans to be stacked along a straight line path of travel, a tray having means for movably mounting the same adjacent one side of said path of travel for receiving said cans, a reciprocable pusher member disposed adjacent the opposite side of said path of travel for pushing a row of said cans transversely of said path of travel and into said tray, means movable with said pusher member for holding back a line of cans on said conveyor means while a row of cans is being pushed into said tray, and means for shifting said tray in opposite directions relative to and longitudinally of said path of travel in time with the reception of each row of cans, the tray thereby receiving adjacent rows of cans in staggered relation.

3. A machine for stacking cans in staggered rows, which comprises in combination, conveyor means for propelling cans to be stacked along a straight line path of travel, a tray having means for movably mounting the same adjacent one side of said path of travel for receiving said cans, a reciprocable pusher member disposed adjacent the opposite side of said path of travel for pushing a row of said cans transversely of said path of travel and into said tray, a depressible guide rail located between said pusher member and

said tray for guiding the cans into place adjacent said pusher member, means for depressing said guide rail in advance of a can inserting movement of said pusher member, and means for shifting said tray in opposite directions relative to and longitudinally of said path of travel in time with the reception of each row of cans, the tray thereby receiving adjacent rows of cans in staggered relation.

10 4. A machine for stacking cans in staggered rows, which comprises in combination, conveyor means for propelling cans to be stacked along a straight line path of travel, a movable tray disposed adjacent one side of said path of travel for receiving said cans, a reciprocable pusher member disposed adjacent an opposite side of said path of travel for pushing said cans in rows transversely of said path of travel and into said tray, a stop element disposed in the path of travel of said cans and movable with said tray for stopping the cans in a predetermined position relative to said tray so that alternate rows of cans segregated by said pusher member will have a different number of cans in the row than in the inbetween rows, and means for shifting said tray in opposite directions relative to and longitudinally of said path of travel in time with the reception of each row of cans for receiving the rows of cans in a staggered relation so that the cans of one row will nest with the cans of adjacent rows to provide a compact can formation in said tray.

15 5. A machine for stacking cans in staggered rows, which comprises in combination, conveyor means for propelling cans to be stacked along a straight line path of travel, a movable tray disposed adjacent one side of said path of travel for receiving said cans, a pusher member disposed adjacent an opposite side of said path of travel for pushing said cans in rows transversely of said path of travel and into said tray, a stop element disposed in the path of travel of said cans, a lever arm connecting with said stop element, a link connecting said lever arm with said tray for shifting said stop element longitudinally of the path of travel of said cans and in time with the movement of said tray for stopping the cans in a predetermined position relative to said tray so that alternate rows of cans segregated by said pusher member will have a different number of cans in the row than the inbetween rows, and means for shifting said tray longitudinally of said path of travel after the reception of each row of cans for receiving the rows of cans in a staggered relation so that the cans of one row will nest with the cans of adjacent rows to provide a compact formation.

20 6. A machine for stacking cans in staggered rows, which comprises in combination, conveyor means for propelling cans to be stacked along a straight line path of travel, a tray having means for movably mounting the same adjacent one side of said path of travel for receiving said cans, a reciprocable pusher member disposed adjacent an opposite side of said path of travel for pushing said cans in rows transversely of said path of travel and into said tray, means for shifting said tray in opposite directions relative to and longitudinally of said path of travel in time with the reception of each row of cans for receiving the rows of cans in a staggered relation so that the cans of one row will nest with the cans of adjacent rows to provide a compact formation, and stop means disposed adjacent the path of travel of said tray for limiting the movement of said tray and

for locating it in a predetermined position to receive the rows of cans in staggered relation.

7. A machine for stacking cans in staggered rows, which comprises in combination, conveyor means for propelling cans to be stacked along a straight line path of travel, a tray having means for movably mounting the same adjacent one side of said path of travel for receiving said cans, a reciprocable pusher member disposed adjacent an opposite side of said path of travel for pushing said cans in rows transversely of said path of travel and into said tray, and pneumatic devices operating against opposite sides of said tray for shifting said tray in opposite directions relative to and longitudinally of said path of travel in time with the reception of each row of cans for receiving the rows of cans in a staggered relation.

8. A machine for stacking cans in staggered rows, which comprises in combination, conveyor means for propelling cans to be stacked along a straight line path of travel, a tray having means for movably mounting the same adjacent one side of said path of travel for receiving said cans, a reciprocable pusher member disposed adjacent an opposite side of said path of travel for pushing said cans in rows transversely of said path of travel and into said tray, a pneumatic cushioning device operable against said tray for holding it in position to receive certain rows of cans, and a pneumatic ram operable against the opposite side of said tray for shifting said tray in one direction relative to and longitudinally of the path of travel of said cans against the resistance of said cushioning device for positioning the tray for the reception of a row of cans, said cushioning device being further operable to thereafter shift the tray in the opposite direction longitudinally of the path of travel of the cans, whereby to insure a different number of cans in alternate rows of staggered relation so that the cans of one row will nest with those of adjacent rows to provide a compact formation.

9. A machine for stacking cans in staggered rows, which comprises in combination, conveyor means for propelling cans to be stacked along a straight line path of travel, a tray having means for movably mounting the same adjacent one side of said path of travel for receiving said cans, a pusher member disposed adjacent an opposite side of said path of travel for pushing said cans in rows transversely of said path of travel and into said tray, a pneumatic cushioning device operable against said tray for holding it in position to receive certain rows of cans, a pneumatic ram operable against an opposite side of said tray for shifting said tray longitudinally of the path of travel of said cans and against the resistance of said cushioning device for positioning the tray for the reception of alternating rows of cans, valve

and vent means connecting with said ram for admitting and releasing air to and from said ram for shifting said tray, and means for actuating said valve and vent means in time with the operation of said pusher member.

5 10. A machine for stacking cans in staggered rows, which comprises in combination, conveyor means for propelling cans to be stacked along a straight line path of travel, a tray having means for movably mounting the same adjacent one side of said path of travel for receiving said cans, a reciprocable pusher member disposed adjacent an opposite side of said path of travel for pushing said cans in rows transversely of said path of travel and into said tray, pneumatic means for actuating said pusher member, and pneumatic devices operating against opposite sides of said tray for shifting said tray in opposite directions relative to and longitudinally of said path of travel in time with the reception of each row of cans so that the cans of one row will nest with the cans of adjacent rows and in staggered relation to provide a compact formation.

20 25 30 35 40 45 11. A machine for stacking cans in staggered rows, which comprises in combination, conveyor means for propelling cans to be stacked along a straight line path of travel, a tray having means for movably mounting the same adjacent one side of said path of travel for receiving said cans, a pusher member disposed adjacent an opposite side of said path of travel for pushing said cans in rows transversely of said path of travel and into said tray, a depressible guide rail located between said pusher member and said tray for guiding the cans into place adjacent said pusher member, an electric solenoid connecting with said guide rail and operable in time with the said pusher member for depressing said guide rail in advance of a can inserting movement of said pusher member, and means for shifting said tray longitudinally of said path of travel after the reception of each row of cans for receiving the rows of cans in a staggered relation so that the cans of one row will nest with the cans of adjacent rows to provide a compact formation.
